Fig. 2

Inventor
George M. Rentsz
By his Attorneys

Merchants Kilgore

UNITED STATES PATENT OFFICE.

GEORGE M. RENTZ, OF WELLS, MINNESOTA.

PHONOGRAPH.

Application filed November 21, 1921. Serial No. 516,850.

To all whom it may concern:

Be it known that I, GEORGE M. RENTZ, a citizen of the United States, residing at Wells, in the county of Faribault and State of Minnesota, have invented certain new and useful Improvements in Phonographs; and I do hereby declare the following to be a full, clear, and exact description of the invention, such as will enable others skilled in the art to which it appertains to make and use the same.

My present invention relates broadly to phonographs and more specifically to the sound amplifier or horn and the cabinet.

15 To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in elevation and partly in central vertical section taken 25 through a phonograph having the invention embodied therein, with some parts shown in different positions by means of broken lines;

Fig. 2 is a view principally in vertical section taken on the line 2—2 of Fig. 1;

30 Fig. 3 is a fragmentary view partly in elevation and partly in vertical section taken on the line 4—4 of Fig. 2, with the main and supplemental covers open;

Fig. 4 is a fragmentary detail view partly 35 in plan and partly in horizontal section taken on the line 4—4 of Fig. 2; and

Fig. 5 is a fragmentary view partly in plan and partly in horizontal section taken on the line 5—5 of Fig. 2.

40 The numeral 6 indicates a cabinet having an open bottom and supported on legs 7 considerably above the floor. The front of the cabinet 6 is closed by a hinged door 8, back of which is a plurality of vertically spaced shelves 9 for holding records or containers for records and it is important to note that said shelves terminate considerably short of the back of the cabinet. At its top, the cabinet 6 is closed by a main cover 10 and a supplemental cover 11 vertically spaced, the former above the latter, to afford a compartment 12 therebetween and which supplemental cover 11 affords a table top, which carries the sound-reproduc-

ing mechanism, as will presently appear. 55 Both covers 10 and 11 are hinged to the back of the cabinet 6 for vertical swinging opening and closing movements.

To hold the main cover 10 in various different open positions, there is provided a 60 counterbalancing device, which includes a toggle link 13, a horizontally disposed pressure lever 14 and a spring 15. One end of the toggle link 13 is pivoted to one side of the main cover 10 and the other end 65 thereof is pivoted to a depending bracket 16 rigidly secured to the bottom of the supplemental cover 11. A grooved wheel 17 is journaled to the toggle link 13, at the joint thereof, and arranged to travel, under the 70 straightening and buckling movements of the toggle link 13, on the upper edge of the forwardly projecting long arm of the lever 14, which is intermediately fulcrumed to the bracket 16 above the pivoted lower 75 end of said toggle link. One end of the spring 15 is attached to the short arm of the pressure lever 14 and its other end is connected to the lower end of the bracket 16 by a thumb-nut-equipped bolt 18, by 80 which the tension of the spring 15 may be varied, at will.

To automatically lift the supplemental cover 11 by the opening movement of the main cover 10 beyond a predetermined position, there is pivoted to the bottom of said supplemental cover, at one side thereof, a depending arm 19 which extends through an aperture in a latch plate 20 on a block 21 secured to the bottom of the supplemental cover 11. In the free end of the arm 19 is a latch notch 22 arranged to interlock with the latch plate 20, when the main cover 10 is raised beyond a predetermined position, and thereby connect the supplemental cover 11 to the main cover 10, so 85 that further opening movement of said main cover will automatically raise the supplemental cover 11 and support the same, as shown by broken lines in Fig. 1. To prevent the arm 19 from accidentally slipping out of interlocking engagement with the latch plate 20, there is formed in said latch plate, back of the aperture, a small aperture 23 for receiving the heel of said arm 90 at its latch notch 22, as shown by broken lines in Fig. 1.

The reproducing mechanism heretofore

referred to includes a motor 24, a record-holding turn-table 25, a sound box 26 and a tone arm 27, the latter of which is swiveled in a bearing 28, secured to the top of the 5 supplemental cover 11 at the back thereof, for horizontal swinging movement over the turn-table 25. This turn-table 25 is carried by a post 29, which extends from the motor 24 through an aperture in the supplemental cover 11 and which motor is attached to the bottom of said cover. The end of the tone arm 27, mounted in the bearing 28, extends into an aperture 30, which extends completely through the supplemental 10 cover 11.

The reproducing mechanism just described is of standard and well known construction. Rigidly secured to the bottom of the supplemental cover 11 is a channel 20 guide 31 having in its bottom an aperture 32 axially aligned with the swiveled end of the tone arm 27, and mounted in said guide is a sliding gate 33 which completely fills said channel guide and is provided with an 25 aperture of the same size as the apertures 30 and 32, between which it is located, and which gate may be adjusted to vary the operative size of the aperture in said gate. To operate and hold the gate 33 in different 30 adjustments, the same is provided with a screw 34 having a knurled head and extending through a slot 35 in the supplemental cover 11, where it may be easily operated. Said screw 34 is provided with an annular 35 shoulder 36 arranged to bear against the top of said cover when the screw 34 is turned down and thereby frictionally clamp the gate 33 to the under side of the cover 11.

Within the cabinet 6, back of the shelves 9, 40 is a sound amplifier 37, commonly called a "horn," of novel construction. This horn 37 is in communication with the tone arm 27 and is open at its bottom so that the sound therefrom passes through the open bottom 45 of the cabinet out into the room on all sides thereof. The horn 37, as shown, is of double formation and resembles a horseshoe as to form and the downturned ends thereof are open. In the crown of the horn 37 is a 50 throat block 38, the opening in which is in registration with the tone arm 27 through the apertures 30 and 32 and the gate 33, which, in reality, form portions of the throat connection between the tone arm 27 and the horn 37. Extending transversely 55 through the horn 37, below its throat 38, is a wedge-shaped sound deflector 39.

To permit the supplemental cover 11 to be lifted without disturbing the horn 37, said horn is yieldingly suspended from the cabinet 6 by a leaf spring 40 intermediate secured to an offset 41 on the throat block 38, with its ends engaging a block 42 secured to the back of said cabinet. This 60 block 42 is notched to receive the throat

block offset 41 and holds the crown of the horn 37 against lateral movement but permits free vertical movement of said horn under the action of the spring 40. Blocks 70 43, on the back and sides of the cabinet 6, hold the lower end portion of the horn 37 against lateral movement but with freedom for the required vertical movement. The spring 42 holds the throat block 38 yieldingly pressed against the bottom of the channel guide 31 when the supplemental cover 11 is closed, and a pliable packing 44 is interposed therebetween to afford a tight 75 joint.

When the supplemental cover 11 is raised, 80 the channel block 31 moves away from the throat block 38 without disturbing the horn 37, with the exception that said horn is slightly lifted by the spring 40 so that when the supplemental cover 11 is again closed, the horn 37 is depressed against the action of the spring 40 and thereby forms a tight joint between the channel guide 31 and the throat block 38.

From the above description, it is evident that, by opening the cover 10, access may be had to the compartment 12 and, by opening said cover beyond a predetermined point, the supplemental cover 11 may be 90 opened to afford access to the interior of the cabinet 6, motor 24 and horn 37 without disturbing any of the mechanism. By adjusting the gate 33, the volume of sound 95 may be controlled and, as previously stated, the horn 37 has downturned open ends so that the sound emitted therefrom enters the room from the four sides of the cabinet 6 and is thereby directed in all directions into the room. Phonographs are now designed 100 with horns arranged to emit sound into a room in one direction only, thus making it difficult to hear in all parts of the room and it often happens that a person standing directly in front of the sound amplifier, when 105 he is operating the phonograph or selecting the record, muffles the sound. The arrangement of the horn 37 also permits the use of the entire front of the cabinet 6 for records.

What I claim is:

1. The combination with a cabinet having a displaceable table top, of a tone arm mounted on the table top, a sound amplifier with which the tone arm has communication through a passageway in the table top, and yielding means entirely suspending the sound amplifier from its receiving end within the cabinet and under strain to lift the same, said sound amplifier being arranged to be engaged by the table top and depressed thereby to form a tight joint therebetween.

2. The combination with a cabinet having an abutment and a displaceable table top, of a tone arm mounted on the table top, and a sound amplifier with which the tone arm has communication through a passageway

in the table top, said sound amplifier having at its receiving end a lateral offset, a leaf spring supported on said abutment and yieldingly suspending the sound amplifier, 5 said sound amplifier being arranged to be engaged by the table top and depressed thereby to form a tight joint therebetween.

3. The structure defined in claim 2 in which the sound amplifier is vertically guided by the abutment. 10
In testimony whereof I affix my signature.

GEORGE M. RENTZ.
